Geo R Kelsey

UNITED STATES PATENT OFFICE.

GEORGE R. KELSEY, OF WEST HAVEN, CONNECTICUT.

IMPROVEMENT IN BUCKLES.

Specification forming part of Letters Patent No. 55,311, dated June 5, 1866.

To all whom it may concern:

Be it known that I, GEORGE R. KELSEY, of West Haven, in the county of New Haven and State of Connecticut, have invented a new and useful Improvement in Buckles; and I do hereby declare that the following is a full, clear, and exact description of the construction, character, and operation of the same, reference being had to the accompanying drawings, which make part of this specification, in which—

Figure 1 is a perspective view of the obverse side of the buckle when complete and ready for use and sale. Fig. 2 is a perspective view of the reverse side of the buckle when complete. Fig. 3 is a perspective view of the reverse side of the frame of the buckle, ready to receive the tongues, showing the socket parts partially turned for that purpose. Fig. 4 is a perspective view of the tongues and their connection as ready to be attached to the frame.

My improvement consists in making the buckle of two pieces—that is, I make the frame or bow and loop or slide with the sockets of one piece of sheet metal and the two tongues and their connection of one piece of wire—and in putting them together in such a manner as to form a buckle with a bow and loop or slide of substantially the same width, so as to give it a neat and symmetrical appearance when in use.

I make the frame or bow and loop or slide of one piece of sheet metal by cutting or swaging it into the proper shape or form with suitable dies, as shown at *a* and *b*, Figs. 1, 2, and 3, so that the running part of the strap or webbing may be passed up through the bow *b* onto the tongues *c* and *c*, and then down again through and under the loop or slide *a*, as indicated by dots in Fig. 1, so that the end of the running

part of the strap or webbing will be secure, and the parts of the buckle-frame will appear symmetrical or equal on all sides.

I cut and swage the sheet metal in such a manner that the parts which are to constitute the sockets to receive and hold the tongues are cut and turned up, as represented at *d* and *d*, Fig. 3.

I make the two tongues *c* and *c* and their connection *e* (or portion to which the standing part of the strap is to be attached) of one piece of wire, bent or formed substantially into the shape shown in Fig. 4, and sharpen the points in a proper manner, as appears in Figs. 1 and 4, the tongues *c* and *c* and connection *e* being substantially the same in shape and construction as described in a patent issued to Sheldon S. Hartshorn, July 10, 1855, and now owned by the West Haven Buckle Company.

Having made the two parts as before described, I place the tongue part, Fig. 4, into the frame, Fig. 3, in such a position that the socket parts *d* and *d* may, by the use of proper dies, be closed around the wire to form a suitable socket, as shown at *d* and *d*, Fig. 2, and indicated at *d* and *d*, Fig. 1, when the buckle will be complete, and will appear on its reverse side as represented in Fig. 2 and on the obverse side as represented in Fig. 1, and will be ready for use or sale.

What I claim as my invention, and desire to secure by Letters Patent, is—

The combination of the frame, Fig. 3, with the tongues, Fig. 4, when they are constructed, attached, and fitted for use substantially as herein described and set forth.

GEO. R. KELSEY.
